Application July 11, 1936, Serial No. 90,236
In Belgium July 13, 1935

13 Claims. (Cl. 230—56)

This invention relates to internal-combustion motor compressor units of the free and opposed piston type, meaning thereby motor-compressors comprising motive pistons adapted to compress a gaseous medium without the interposition of rotating machine parts. It relates more particularly to units of this type comprising at least one compression stage, and still more particularly, to such units of the asymmetrical type, meaning thereby motor-compressors in which each compression stage comprises only one compressor cylinder and co-acting piston, as opposed to the symmetrical type, in which each compression stage comprises two identical compressor cylinders and coacting pistons symmetrically disposed with respect to, and at opposite ends of, the motor cylinder. It also applies incidentally to motor compressors of the type described which are used to generate a power-conveying compressed gas to be subsequently used in a heat engine, such as a gas turbine.

The main purpose of my invention is to simplify the construction of said devices, and to reduce their weight, bulk and manufacturing cost.

The principal object of my invention is to provide a motor-compressor unit of the asymmetrical opposed piston type, as hereinbefore defined, in which the kinetic energy imparted to the motive pistons by the combustion of the fuel is transmitted to a single reciprocating compressing assembly, directly by one of said motive pistons, that is through the medium of a rigid operative connection, and by the other motive piston, through the medium of a motion-reversing operative connection also adapted to synchronize the relative reciprocating motion of said two motive pistons, said compressing assembly comprising at least one compressor piston co-acting with at least one compressor cylinder.

Another object is to provide a motor-compressor unit of the type described, in which said motion-reversing energy transmitting and synchronizing operative connection is adapted to perform its double function without the resulting strains induced therein exceeding by more than a small amount those resulting solely from the inertia of the reciprocating parts.

A further object is to provide a motor-compressor unit of the type described, comprising pneumatic energy storage or cushioning means for supplying at least part of the energy required for the return stroke of the motive pistons.

A still further object is to provide a motor-compressor unit of the type described, in which said pneumatic energy supplying means are so

dimensioned as to be adapted to simultaneously supply at least part of the energy for the return stroke of motive pistons, and to so regulate the forces transmitted by said motion-reversing and synchronizing operative connection to the reciprocating compressing assembly that said forces will not exceed a relatively small function of the forces exerted on the motive pistons.

A still further object is to provide a single stage motor-compressor unit of the type described, in which said pneumatic energy-supplying means consist in a single pneumatic cushioning cylinder and co-acting piston, the compressor cylinder and co-acting piston being disposed at one end of the motor cylinder, and the pneumatic cushioning cylinder at the other end of said motor cylinder, the capacities of said pneumatic cushioning cylinder and compressor cylinder being so related as to limit the forces transmitted by said motion-reversing and synchronizing operative connection to a relatively small fraction of the forces acting on the motive pistons.

A still further object is to provide a three stage motor-compressor unit of the type described, in which the low-pressure stage and the pneumatic cushioning cylinder are disposed at one end of the motor cylinder, and the medium and high-pressure stages at the other end of said motor cylinder, the capacities of said compressor stages and pneumatic cushioning cylinder being so related as to limit the forces transmitted by said synchronizing operative connection to a relatively small fraction of the forces acting on the motive pistons.

A still further object is to provide a single or multiple stage motor-compressor of the type described, also adapted to function as a power conveying gas generator, in which said pneumatic cushioning cylinder, located, in the single-stage type, on the opposite end of the motor cylinder from that of the single compressor cylinder, and in the multiple stage compressor, at the same end of the motor cylinder as the lowest pressure compressor cylinder, is adapted to function at will as a two-stroke-cycle internal combustion engine, the fuel injection therein being regulated, according to the delivery pressure of said motor-compressor unit, in such a manner that, when said delivery pressure exceeds a given limit, the injection of fuel in said cushioning cylinder will be reduced or stopped, said cushioning cylinder thereafter operating in the known manner as a pneumatic cushion insuring the stability of the unit under reduced loads and down to no-load.

A still further object is to provide a motor-

25

30

35

40

45

50

55

compressor unit of the type described, in which the auxiliary pneumatic cushioning cylinder is replaced by a second motor cylinder co-acting with two opposed motive pistons.

5 Other objects and advantages of my invention will appear to one skilled in the art, from the following description, with reference to the accompanying drawings, it being understood, of course, that said description and drawings are 10 given by way of illustration, and should not be construed as limiting the scope of my invention.

In these drawings:

Fig. 1 shows diagrammatically, in axial cross-section, a single-stage asymmetrical motor-compressor embodying my invention, and comprising a single compressor stage and a single auxiliary compensating pneumatic cylinder;

Fig. 2 shows schematically the linear and angular displacements of the kinematic synchronizing 20 and motion-reversing operative connection between said motive pistons.

Figs. 3, 4, 5, 6, and 7 show diagrams of the forces transmitted by said synchronizing and motion-reversing connection.

25 Fig. 8 shows diagrammatically, also in axial cross-section, another embodiment of my invention.

Fig. 8a shows a part of a modification of the form shown in Fig. 8.

30 Figs. 9 and 10 show various pressure-stroke diagrams for this arrangement.

Fig. 11 shows, also in axial cross-section, a three-stage motor-compressor of the type described, comprising a single auxiliary compensating pneumatic cylinder.

Fig. 12 shows, also in diagrammatic axial cross-section, a motor-compressor unit of the type adapted to operate as a free-piston power conveying gas generator, as hereinafter described, 40 also embodying my invention and comprising a single pneumatic energy accumulator adapted for use as a power-generating cylinder.

Fig. 13 shows, in diagrammatically axial cross-section, a double motor-compressor unit comprising two distinct motor cylinders co-acting with two groups of oppositely reciprocating pistons.

Fig. 14 shows a detail of the synchronizing and power transmitting operative connection, as applied to the motor-compressor unit shown in Fig. 13.

One of the essential characteristics of free piston engines is that they comprise no flywheel or other rotating parts, the reciprocating piston assemblies acting themselves as accumulators of energy in order to transmit said energy from the combustion chamber to the compressed gas reservoir. This type of transmission mechanism is therefore adapted to transmit energy under exceptionally favorable conditions insofar as concerns regularity and efficiency, for the energy stored in kinetic form by the reciprocating assemblies under the action of the very high pressures of the motive gases during the combustion period 65 is transferred only gradually by said assemblies to the gaseous medium to be compressed, whereas in engines comprising rotating crankshafts and co-acting connecting rods driving a flywheel, the rapidly fluctuating forces to which the pistons are subjected are instantly and integrally transferred to the connecting rods and crankshaft whose function it is to overcome the inertia of the flywheel and accelerate the same.

Furthermore, when the motive parts of free 70 piston engines consist of two pistons movable in

opposite directions, it is necessary to synchronize said pistons through the medium of kinematic connections; and said connections must be of sufficient strength to be able to transmit, in case one of the pistons should bind, all the energy imparted to the other piston.

More particularly, when said kinematic connections consist of connecting rods articulated to oscillating cranks, they may advantageously be used simultaneously to insure the synchronization of the reciprocating pistons, and as a safety device limiting the maximum length of stroke, in case the resistance of the air cushions should fall.

In this last case, it may be shown that the connecting linkages may have to withstand considerable forces. The result is that said kinematic connections, if designed to operate both as a safety device and as synchronizing means, may be also used to transmit considerable amounts of power without the forces which they must transmit exceeding by more than a small amount the forces which they must be able to withstand when acting only as synchronizing and safety devices. It may thus be shown that, when the power transmitted by said connections equals one half of that generated in the motor cylinder, which is the case in motor-compressors having two motive pistons and only one compressor piston, the forces transmitted by said kinematic connections may be of the order of one sixth to one tenth of the maximum forces exerted on the pistons.

When the pneumatic energy storage means, in accordance with my invention, are located and dimensioned as specified hereinafter, the forces transmitted by said connections may be so reduced as not to exceed the maximum strains to which they are normally subjected in symmetrical motor-compressors simply in overcoming the inertia of reciprocating parts, although they transmit no useful work in said symmetrical units.

To this end, in accordance with one of the preferred forms of my invention, the engine portion of the unit consists of a motor cylinder 1, within which reciprocate in opposite directions two axially slidable motive pistons 2₁ and 2₂, piston 2₁ being rigidly connected with at least one compressor piston 3 co-acting with at least one compressor cylinder 4, and piston 2₂ being rigidly connected with the auxiliary piston 5 of the pneumatic cushioning means 6.

The piston assemblies 2₁-3 on one hand, and 2₂-5 on the other hand, are designed of exactly the same mass, in order to balance the machine, said masses being computed so as to adapt said assemblies to store in kinetic form the expansive energy of the burnt gases and to surrender the same progressively to the gaseous medium to be compressed. Part of said power is thus transferred directly to said gaseous medium by the assembly 2₁-3, and all or part of the energy stored in the assembly 2₂-5 may be transmitted to the assembly 2₁-3 by the kinematic connections consisting, for example, of connecting rods 10₁ and 10₂ and cranks 11.

From extreme angular positions of the connecting rods 10₁ and 10₂ and of cranks 11, as indicated in Fig. 2, may be computed the strains due to inertia which are transmitted by the reciprocating assemblies to said kinematic connections (see curve A B C D in Fig. 3).

It may be seen that, during the first part A B of the stroke, said connections must withstand a powerful force due to the acceleration of the reciprocating assemblies, whereas, during the second part B C of the stroke, the inertia effects

are small; and finally, during the last part C D of the stroke, the acceleration of the reciprocating parts reverses the forces transmitted by said connections.

- 5 For certain volumetric and manometric characteristics of compressor 4 and cushioning cylinder 6, corresponding to equal forces exerted at the outer dead centers on pistons 3 and 5, the diagrams shown in Fig. 4 (M N P Q for the 10 compressor cylinder and M P for the pneumatic cushion) indicate the total pneumatic forces to which are subjected pistons 3 and 5 during the complete cycle of the unit (force f_c on piston 3 and f_m on piston 5).
 15 It may be seen that, during the working stroke, the compressor piston 3 is subjected to forces which are superior to those exerted on piston 5 of the auxiliary cushioning cylinder 6, and that, on the contrary, during the return stroke, 20 the piston 5 is subjected to greater forces than the piston 3. The difference between these forces (that is, the difference between corresponding ordinates in the diagram) is transmitted by the kinematic connections.
 25 The diagram of Fig. 5 shows the differential strains at different points of the working stroke ($m n r$) and of the return stroke ($r q_1 m$).

The superposition of the forces indicated in the diagrams of Figs. 3 and 5 gives the resultant 30 forces to which the kinematic connections will be subjected in all their positions (curve I J K L O J D). It is seen that, in the case under consideration, the total forces to which are subjected said connections are relatively small and 35 may even never exceed the maximum due to the inertia effect for which the kinematic connections have been designed. Said connections are therefore adapted to transmit the difference between the resisting forces produced by the 40 compressor 4 and the auxiliary cylinder 6.

In general the kinematic connections are designed to transmit forces greatly in excess of those due to inertia; therefore the manometric and volumetric conditions of compressor 4 and 45 auxiliary cylinder 6 may be chosen such that the power transmitted by said kinematic connections will, on the average, be very low, and the maximum force at the outer dead center may be allowed to exceed slightly that due to 50 inertia.

For example, as shown in Fig. 7, the auxiliary compensating cylinder 6 may be designed so that the maximum differences between the forces exerted on compressor piston 3 (M N P Q) 55 and auxiliary piston 5, (M P' M) will be substantially equal (differences indicated by curve p_1 , p_2 , p_3). For example, for a delivery pressure of the compressor equal to 7 atmospheres, if the ratio between the diameters of compressor cylinder 4 and auxiliary cylinder 6 be made equal to 1.15, the maximum force transmitted from one piston assembly to the other will only be about 550 pounds, whereas the maximum force exerted on the motive pistons will exceed 5,000 60 pounds.

In another embodiment of my invention illustrated in Fig. 8, the power transferred by the kinematic connections and the maximum strain to which they are subjected may be further reduced by feeding the auxiliary pneumatic cylinder 6 at a pressure higher than atmospheric pressure, for example, by connecting said cylinder to the delivery of the compressor at or near the inner dead center.

75 It may be seen by the diagram of Fig. 9 that

the maximum difference between the forces acting respectively on pistons 3 and 5 may be very small, and that, by adopting suitable manometric and volumetric conditions for the capacities 4 and 6, the maximum differences p_1 and p_2 may be made substantially equal; for example, when the delivery pressure is 5 atmospheres, by adopting a ratio between the diameters of pistons 3 and 5 equal to 2.5.

According to another variant, a constant pressure may be used in said auxiliary compensating cylinder 6 during all or part of the stroke, for example, by locating the connection between cylinder 6 and the delivery of the compressor at a suitable point of the stroke of piston 5 as shown in Fig. 8a; in this manner the maximum differences p_1 and p_2 may be made substantially equal, as shown in Fig. 10.

In multi-stage motor-compressor units such as that illustrated, by way of example, in Fig. 20 11, in accordance with my invention, I locate the auxiliary compensating cylinder 6 at the same end of the motor cylinder as the low-pressure compressor cylinder 4₁, and adjacent to the same. For example, if said unit comprises 25 3 stages, the low-pressure stage and the auxiliary compensating cylinder are placed at one end of said motor cylinder, and the intermediate and high-pressure stages 4₂ and 4₃ at the other end.

Contrary to the known practice heretofore, which consisted in balancing the forces acting on the respective reciprocating assemblies by suitably choosing the volumetric and manometric ratios of the different stages, I prefer to 30 retain for said stages the normal ratios corresponding to the maximum compressor efficiency (that is pressure ratios in geometric progression); and, in accordance with my invention, I dimension the auxiliary compensating cylinder 40 6 so as to adapt it to reduce the forces transmitted by the kinematic connections.

Although part of the power generated is transmitted by said kinematic connections, it is well known that the mechanical efficiency of this type 45 of transmission is excellent so that the overall efficiency of the motor-compressor unit is higher than if the volumetric and manometric ratios of the different stages had been specially chosen to reduce to a minimum the forces transmitted by the kinematic connections.

In any case, the elements of the kinematic connections transmitting forces, however small the latter may be, may advantageously be disposed symmetrically with respects to the longitudinal plane of symmetry of the unit, in order to avoid the formation of torsional couples.

Contrary to the arrangement generally adopted in symmetrical motor-compressor units, wherein the connecting rods articulated to two symmetrical cranks are crossed, in asymmetrical units of the type under consideration, I prefer to articulate symmetrical connecting rods such as 10₁ and 10₂, in pairs, to a common axis 12 to which they may advantageously be rigidly connected as shown in Fig. 8, said axis revolving in long bearings formed integrally with the piston assemblies. Each pair of rods thus forms with the axis 12 a rigid frame which makes it possible to reduce, and even to eliminate, sliding guides.

It is also possible in accordance with my invention, to impart to the respective piston assemblies reciprocating displacements of unequal but proportional amplitudes. I attain this end by making said assemblies of different masses,

5

10

15

20

25

30

35

40

45

50

55

60

65

70

75

for example, by making them of different materials having different densities. Under these conditions, the relative momenta of the two assemblies remain equal at all points of the cycle, that is, their velocities are inversely proportional to their masses.

It is also possible, as shown in Fig. 11, to use unsymmetrical cranks 11.

In the case where the strokes of the piston assemblies are different, I prefer to impose the longest stroke to the assembly which comprises the hottest of the two motive pistons, that is, the motive piston closest to the exhaust ports, in order to intensify the cooling influence of the cylinder walls on said piston.

In motor-compressor operating on the two-stroke cycle, it is necessary to provide, in addition to the energy-absorbing capacities 4 and 6, at least one scavenging pump, which pump may advantageously consist, as in Fig. 1, of the rear end of the compressor cylinder 4, limited by the inactive face of piston 3, forming a chamber 15 in which air may be compressed on the inward stroke of piston 4 and fed into space 9 around the motor cylinder. It is evident that, in this case, the energy absorbed by the scavenging compressor is deducted from that available for the main compressor.

It is also possible, as shown in Fig. 1, to use part of the scavenging air to feed the auxiliary compensating cylinder 6, said air being introduced in said cylinder in any suitable manner; for example, by means of slots 17 cut in the rigid connection between motive piston 2 and auxiliary piston 5; or by such means as duct 18 or its equivalent when the piston 5 is at the inner dead end of its stroke, scavenging air may flow from space 9 through slots 17 and duct 18 into space 6.

40 In the special embodiment of my invention illustrated in Fig. 12, the pneumatic cushioning cylinder 6 is adapted to function at will either as an ordinary energy storing compensating device, or as a power-generating two-stroke-cycle internal-combustion engine cylinder. To this end, said cylinder 6 is provided with a scavenging and combustion air intake 21 and valve 22, fuel injection means 23 and exhaust ports 24.

In this embodiment, I have also shown a motor-compressor unit adapted to the particular function of generating a gaseous medium under pressure and at relatively high temperature, which gaseous medium is to be subsequently used to operate a heat engine of any suitable type, such as, for example, a gas turbine. This special type of motor compressor I prefer to call a free and opposed piston power-conveying gas generator.

60 In the embodiment illustrated in Fig. 12, the single compressor unit, formed by compressor piston 3 co-acting with compressor cylinder 4, is made double acting, and delivers the air compressed into the storage reservoir 1^a formed by the closed casing. At the end of the working stroke, the motive pistons uncover the intake ports 19^a and exhaust ports 19^b. The air stored under pressure in casing 1^a penetrates into the motor cylinder 1 and passes out by the exhaust manifold 20, entraining the exhaust gases, the mixture of compressed air and exhaust gases at high temperature being subsequently expanded in the heat engine.

Insofar as concerns the auxiliary pneumatic cylinder 6, when it functions as a combustion engine cylinder, the compressed air from casing

1^a passes through said cylinder 6 at the end of the working stroke, sweeping the burnt gases out through the exhaust manifold, where they mix with the exhaust from the main motor cylinder.

5 In Fig. 13, I have shown still another embodiment of my invention, wherein the auxiliary pneumatic compensating cylinder is discarded and replaced by a second free piston motor unit of similar design to that of the first motor unit, and connected therewith in tandem combination by suitable synchronizing and power transmitting kinematic connections, which are illustrated diagrammatically in Fig. 14, said kinematic connections being adapted to transmit all or part of the power generated in both motor cylinders 15 to one single compressor piston 3.

10 The combined tandem motor unit comprises two motor cylinders 1 and 26, each co-acting with two opposed pistons, 2¹ and 2² in the first cylinder, and 27 and 28 in the second. Piston 2² is rigidly connected to piston 28, and motor pistons 2¹ and 27, and compressor piston 3 are interconnected by means of the afore mentioned kinematic linkages consisting of connecting rods 10¹, 10², 10^{1a}, 10^{2a}, co-acting with cranks 11 and 11^a. Said kinematic system is shown in Fig. 14 in skeleton form, that is omitting the motor units. The linkage system is articulated at two fixed points I and II, abreast of the two centers of the motor cylinders 1 and 26.

20 It should be understood that I do not wish to be limited to the structural details described and illustrated, for obvious modifications thereto will occur to persons skilled in the art.

25 What I claim is:

30 1. An internal combustion engine compressor with opposed free pistons having asymmetrical distribution of the compressor chambers, and a synchronizing linkage connecting said pistons, additional compensating cushioning means separated from the interior of the compressor chamber, said last means being also asymmetrically disposed in such a manner that the power, that is to be transmitted by the synchronizing linkage from one end of the internal combustion engine compressor to the other end thereof, produces a strain in the synchronizing linkage which is at most about equal to the maximum strains to which the synchronizing linkage is subjected under the action of the inertia forces even without transmission of power.

35 2. A single stage internal combustion engine compressor according to claim 1, said last means comprising a single compensating cushion arranged at one end of the internal combustion engine compressor, the compressor cylinder at the end opposite the compensating cushion serving for the production of air for use.

40 3. A multi-stage internal combustion engine compressor according to claim 1, said last means comprising a compensating cushion at the same end as the compressor cylinder of the lowest pressure stage, and a plurality of compressor cylinders of higher compressor stages arranged at the opposite end of the compressor.

45 4. A single stage internal combustion engine compressor according to claim 1, said last means comprising a single compensating cushion arranged at one end of the internal combustion engine compressor, the compressor cylinder at the end opposite the compensating cushion serving for the production of air for use, said compensating cushion being so proportioned that the maximum differences between the pressure loads, which act on the piston of the cushion and on the

piston of the compressor cylinder are approximately equal.

5. An internal combustion engine compressor according to claim 1, in which the initial pressure in the compensating cushion is above the surrounding pressure.

6. An internal combustion engine compressor according to claim 1, in which the pressure in the cushion is, during a first part of the stroke, kept constant at a value above the external pressure and then rises.

7. An internal combustion engine compressor according to claim 1, in which the synchronizing linkage comprises two linkage portions which lie on the two sides of the compressor and each of which comprises a rocking lever pivoted about a stationary axis and two connecting rods connecting the rocking lever with the opposed pistons, the connecting rods of the two linkage portions lying parallel to each other in all positions.

8. An internal combustion engine compressor according to claim 1, in which the synchronizing linkage comprises two linkage portions which lie on the two sides of the compressor and each of which comprises a rocking lever pivoted about a stationary axis and two connecting rods connecting the rocking lever with the opposed pistons, the connecting rods of the two linkage portions lying parallel to each other in all positions, the ends of the connecting rods of the two linkage portions which act on the same piston being keyed to an axle which is rotatably mounted in the

corresponding piston, so that each pair of connecting rods forms a rigid frame with the corresponding axle.

9. An internal combustion engine compressor according to claim 1, in which the oppositely reciprocating free pistons perform strokes of different length and are made of materials of different specific gravities.

10. An internal combustion engine compressor according to claim 1, in which the oppositely reciprocating free pistons perform strokes of different length, the piston subject to the greater heat and located on the exhaust side of the motor cylinder performing the larger stroke.

11. An internal combustion engine compressor according to claim 1, in which the oppositely reciprocating free pistons perform strokes of different length, and the rocking levers of the synchronizing linkage being rotatable about a stationary axis and having unequal arms.

12. An internal combustion engine compressor according to claim 1, in which the compensating cushion means is capable of operating as an internal combustion engine cylinder.

13. An internal combustion engine compressor according to claim 1, in which the compensating cushion means comprises a second motor cylinder with two co-acting opposed motive pistons, and a synchronizing linkage connecting said last motive pistons to the first motive pistons and to said compressor pistons.

RAUL PATERAS PESCARA.
